HOLDER FOR FINGERNAIL FILES

William Stinson, Vancouver, British Columbia,
Canada

Application February 7, 1944, Serial No. 521,415

4 Claims. (Cl. 132—76.5)

The invention relates to a file holder and more especially to a finger nail file holder.

The primary object of the invention is the provision of a holder of this character, wherein a sand-paper finger nail file can be conveniently held for the easy use thereof in filing the nails on the fingers of a hand, the file being easily released for replacement of a new one when the occasion requires.

Another object of the invention is the provision of a holder of this character, wherein the receiver blade for the file is foldable into a handle part of the said holder, so that the latter will be compact and can be conveniently carried on the person or within a pocket book or other like receptacle handy for use.

A further object of the invention is the provision of a holder of this character, which is unique in construction, thoroughly reliable and efficient in its purpose, enabling the easy handling of the file, strong, durable, and inexpensive to manufacture.

With these and other objects in view the invention consists in the features of construction, combination and arrangement of parts as will be hereinafter more fully described, illustrated in the accompanying drawing, which discloses the preferred form of the invention, and pointed out in the claims hereunto appended.

In the accompanying drawing:

Figure 1 is a side elevation of the holder constructed in accordance with the invention and in open position for the use of the file therein.

Figure 2 is an edge view.

Figure 3 is a sectional view taken on the line 3—3 of Figure 2 looking in the direction of the arrows.

Figure 4 is a side view showing the holder folded.

Figure 5 is an enlarged sectional view taken on the line 5—5 of Figure 4, looking in the direction of the arrows.

Figure 6 is a plan view in detail of the retainer clip of the holder.

Figure 7 is a similar view looking toward the other side.

Figure 8 is a perspective view of a guide for the clip.

Figure 9 is a perspective view of the runner thereof.

Similar reference characters indicate corresponding parts throughout the several views in the drawing.

Referring to the drawing in detail A designates generally the holder constituting the pres-

ent invention and comprises a handle part 10 having pivoted at 11 in one end a foldable blade-like file receiving part 12 which is adapted to swing into the handle part 10 when not in use 5 similar to a knife blade of an ordinary foldable pocket knife.

The part 12 is cut into through one edge to form a windowed cavity 13 for a major portion of the length thereof for receiving a sand paper file 14. The inner end of the cavity is rounded at 15 and has fitted thereto a springy contact yoke 16, while the opposite outer end 17 is formed with an inner rounded notch 18. The yoke 16 and the notch 18 accommodate the rounded ends 15 of the file when inserted in the cavity 13 for the retention thereof in the part 12.

Fitted to the end 15 is a wedge action gripper 19 which is pivoted at 20 and is equipped with a compressor runner 21 movable on guides 22 and 20 such runner wedges the gripper 19 against the file 14 when inserted in the cavity 13 when the part 12 is unfolded for securely holding the said file 14 in workable position, as the abrasive sides thereto are exposed through the windows in said 25 part 12 at opposite sides of the same to enable the convenient filing of finger nails on manipulation of the holder A. The runner 21 rides onto the wedging wings 23 of the gripper 19 for releasably clamping the file 14 in the part 12 firmly therein.

30 The runner 21 has a finger lug 24 so that the runner can be moved by hand.

The part 12 is folded into the handle part 10 when the holder A is not in use and thus the latter can be conveniently carried on the person, 35 or in a hand bag or the like.

The end 17 exteriorly thereof has formed thereon a pointed cleaning tip 26 for removing dirt or the like from beneath the nails of a hand.

From the foregoing, it will be understood that 40 as the holder 12 is open at its lower edge, and as the slot 25 of the gripper 19 is open when the runner 21 is retracted, the file 14 may be readily inserted into the holder with its front end in the notch or recess 18, its rear end in contact with

45 the curved spring 16, and its upper edge in the longitudinal groove 13 formed in the back of the holder. The spring 16 functions to hold the file 14 in place until the slider 21 is moved forwardly to close the slot 25 of the gripper 19 and to move 50 the gripping elements 23 into engagement with the sides of the file.

What is claimed is:

1. A device of the character set forth, comprising a holder open at its sides and lower edge and provided at one end with a recess, a spring

located within the other end of the holder in facing relation to the recess, a file carried by the holder with one end in the recess and the other end in contact with the spring, and file retaining means at that end of the holder carrying the spring.

2. A device of the character set forth, comprising a holder open at its sides and lower edge and provided at one end with a recess, the holder being provided in the lower side of its back with a longitudinal groove, a spring located within the other end of the holder in facing relation to the recess, a file carried by the holder with one end in the recess and the other end in contact with the spring, an edge of the file being located in the groove, and file retaining means at that end of the holder carrying the spring.

3. A device as described in claim 1, wherein the file retaining means comprises gripping elements located at opposite sides of the file and a runner for moving and holding said elements in engagement with the file.

4. A device of the character set forth, comprising a holder open at its sides and lower edge and provided at one end with a recess, the back of the holder being provided in its inner side with a longitudinal groove, a file carried by the holder with one end in the recess and one longitudinal edge in the groove, and means carried by the other end of the holder and releasably engaging the file to retain it in place.
